SHOWER-BATH FIXTURE.

1,148,968.

Specification of Letters Patent.

Patented Aug. 3, 1915.

Application filed April 29, 1915. Serial No. 24,710.

To all whom it may concern:

Be it known that I, VINCENT F. JABLONSKI, a citizen of the United States, and a resident of New York, borough of Brooklyn, county of Kings, and State of New York, have invented a certain new and useful Improvement in Shower-Bath Fixtures, of which the following is a full, clear, and exact specification.

10 This invention relates to a class of apparatus adapted to be used for bathing purposes.

My invention has for its object primarily to provide an apparatus, or fixture designed 15 to be employed to permit persons of various heights to take a shower bath in a manner whereby the shower may be caused to flow on any desired part of the body so that wetting the hair especially of a woman bather 20 may be avoided, and which is constructed so as to be adaptable for use in conjunction with bath tubs arranged to receive their supply of water at either the right or left end thereof.

25 The invention consists essentially of a support adapted to be arranged so as to be held stationary adjacent to the receiver of a source of water supply, and on this support above the receiver is a curtain ring which 30 is substantially elliptic in shape to permit the ring to be disposed directly over the receiver when the support is arranged in proximity to either end of the receiver. Also on the support is a curved perforated 35 hollow water spray element provided with an inlet, and one end of this spray element is connected to the support in a manner so as to be adjusted rotatably as well as upwardly and downwardly thereon for distributing the water in the form of a shower.

40 Other objects of the invention are to provide a flexible pipe leading from the source of water supply to the inlet of the spray element; and to provide means whereby the 45 support may be fastened to a wall, or the like.

A practical embodiment of the invention is represented in the accompanying drawing forming a part of this specification in which 50 similar characters of reference indicate corresponding parts in all the views, the said invention being more fully described hereinafter, and then pointed out in the claims at the end of the description.

55 In the drawing, Figure 1 is a side view, partly broken away, of a bath tub showing

the manner of using one form of shower bath fixture embodying my invention in conjunction therewith. Fig. 2 is an enlarged view, partly in section, taken on the line II—II of Fig. 1. Fig. 3 is an enlarged sectional view, partly in detail, taken on the line III—III of Fig. 1, and Fig. 4 is an enlarged top view, partly in section, of the water shower element.

60 The shower bath fixture has a support, or post 10 which may be of a suitable length, and this supporting post is adapted to be disposed so as to be held stationary adjacent to the receiver of the water of an apparatus for permitting persons to take a bath, for instance a bath tub, as 11, which may be arranged to receive water through the faucet, as 12, of a pipe 13 leading from a suitable source of supply at either the right, or 65 left end of the tub, it being customary to apply the water supply fixtures to a bath tub at either one of its ends as occasion requires. The support or post 10 of my shower bath fixture is preferably disposed vertically in 70 proximity to the inlet faucet of the water receiver, or tub, and serving as means to hold the post in a stationary position, two brackets, as 14 and 15, are provided.

75 The bracket 14 has a base-plate 16, which is fastened by screws, or otherwise to a wall, or other support contiguous to the tub, and extending from this base-plate is a short rod having thereon an inverted cap 17 in which the lower end of the post is seated. The 80 bracket 15 has a base-plate 18 which is fastened by screws, or otherwise to the wall, or other support above the bracket 14, and projecting from this base-plate is a rod 19. The rod 19 extends through registered openings 85

20 and 20^a of a union, or sleeve 21 formed with two oppositely projecting apertured bosses 22 and 22^a, and from the sleeve midway between these bosses is a lug 23 having a passage therein communicating with the 90 opening 20 of the sleeve of the bracket 15. The rod 19 of the base-plate 18 is of a length 95 so as to extend also through the passage of the lug 23, and this lug is inserted through an opening 24 so as to extend across the upper part of the recess 25 of a cap 26 which is mounted on top of the supporting post 10. Through the top of the cap 26 is a threaded opening 27 in which is passed a thumb screw 28 adapted to be moved into and out of engagement with the lug 23 for holding the cap, the sleeve 21, and the rod 19 against 100

accidental displacement, and by providing this form of the bracket 15 with the form of bracket 14 the post 10 may be readily mounted on a support as well as being easily removed therefrom when desired.

In order to allow a shower bath curtain, as 29, to be adjustably hung over the receiver, or bath tub so as to be disposed interiorly thereof for use when a person is taking a shower bath, a curtain ring 30 is provided. The ring 30 is preferably substantially elliptic in shape, and when the apparatus, or fixture is arranged for use in conjunction with a tub receiving its water supply at the right end thereof, as shown in Fig. 1, the ring 30 adjacent to its right end is split, at 31, and these split ends of the ring are mounted in the apertures of the bosses 22 and 22^a of the sleeve 21 of the bracket 15. When the apparatus, or fixture is arranged for use in conjunction with a tub receiving its supply of water at the left end thereof the post 10 of the fixture is arranged accordingly adjacent to this end of the tub, and the other end portion of the ring, as at 32, is split instead. These split ends of the ring are then mounted in a similar manner to the bracket 15, and the requirement for employing a bracket as well as the splitting of the ring at its right end portion will thereby be dispensed with. The shower bath curtain is adjustably suspended from the ring by the use of a suitable number of rings 34, or otherwise, and by using the elliptic ring, as explained, the curtain may be disposed so that its lower end will be interiorly of the central part of the tub to prevent water from flowing exteriorly thereof when the bather is taking a shower.

Serving to permit the water to be distributed in the form of a shower on any desired part of the body of the bather without wetting the hair especially of a woman bather, a spray element 35 is provided. The spray element 35 is preferably in the form of a curved hollow tubular pipe-like body having one end closed by a cap, as 36, and at spaced intervals in the concaved part of the wall thereof are perforations, as 37, for distributing the water in a shower. On the other end of the spray element, or perforated pipe-like body 35 is a boss 37^a having a recess 38 communicating with the interior of the perforated pipe-like spray element and this boss has a nipple 39 projecting downwardly for serving as an inlet to admit water into the spray element. On the boss 37 is a sleeve 40 which is guided over the supporting post 10 before the bracket 14 is applied thereto, and this sleeve is of a diameter whereby the spray element 35 may be adjusted rotatably as well as upwardly and downwardly on the post 10. To retain the perforated pipe-like spray element 35 on

the post 10 when in an adjusted position, in a threaded opening in the sleeve 40 is a thumb screw 41 adapted to be moved into and out of engagement with the post, and to permit water to be delivered to the spray element, on its inlet nipple 39 is removably applied one end of a flexible delivery pipe 42 of rubber, or other material having its other end removably applied on the faucet 12 of the pipe leading from the source of water supply, the pipe 42 being of a length to allow the spray element to be elevated to any desired height on the post 10. When a person desires to take a shower bath, and after the curtain is properly adjusted in the water receiver, or tub, the screw 41 of the spray element 35 is loosened from its engagement with the post 10. The spray element 35 may then be guided upwardly and downwardly on the post 10 as well as being rotatably moved circumferentially of the body of the bather following the opening of the faucet of the source of water supply. The water delivered from the faucet through the pipe 42, and through the spray element 35 will thereby be showered on the desired parts of the body of the bather.

In the foregoing description, I have embodied the preferred form of my invention, but I do not wish to be understood as limiting myself thereto as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:—

1. In a shower bath fixture, a post adapted to be fastened to a support in a vertical position adjacent to one end of a bath tub, or other water receiver, a pipe-like spray element having one end movably connected to the support so as to be adjusted upwardly and downwardly thereon as well as being swung circumferentially over the tub whereby water may be showered on the desired parts of the body of a bather, and the said spray element having an inlet for the admission of water, means connected to the inlet, leading from a source of water supply for delivering water to the spray element, two oppositely disposed apertured bosses on the upper end of the post, and a split substantially elliptic ring having its ends inserted in the apertures of the bosses, as set forth and for the purpose specified.

2. In a shower bath fixture, a post, two brackets each having a cap in which the ends of the post are seated, and said brackets being adapted to be fastened to a support in a vertical position adjacent to one end of a bath tub, or other water receiver, a curved

5 pipe-like spray element having one end mov-
ably connected to the support so as to be
adjusted upwardly and downwardly thereon
as well as being swung circumferentially
over the tub whereby water may be showered
on the desired parts of the body of a bather,
and the said spray element having an inlet
for the admission of water, a flexible pipe
means connected to the inlet, leading from
10 10 a source of water supply for delivering wa-
ter to the spray element, two oppositely dis-
posed apertured bosses on the upper bracket
of the post, and a split substantially elliptic
ring having its ends inserted in the aper-
15 tures of the bosses, as set forth and for the
purpose specified.

3. In a shower bath fixture, a post, two
brackets each having a cap in which the ends
of the post are seated, and said brackets be-
20 20 ing adapted to be fastened to a support in a
vertical position adjacent to one end of a
bath tub, or other water receiver, a curved
perforated pipe having one end closed, and

25 having an inlet in its other end to admit
water thereinto, a sleeve on the inlet end of
the perforated pipe, and adjustably movable
on the support whereby the perforated pipe
may be adjusted upwardly and downwardly
30 as well as being swung circumferentially
over the tub so that water may be showered
on the desired parts of the body of a bather,
means connected to the inlet, leading from
a source of water supply for delivering wa-
35 ter to the spray element, two oppositely dis-
posed apertured bosses on the upper bracket
of the post, and a split substantially elliptic
ring having its ends inserted in the aper-
tures of the bosses, as set forth and for the
purpose specified.

This specification signed and witnessed 40
this twenty eighth day of April A. D. 1915.
